VALVE MECHANISM

Clyde H. Folmsbee, Charlevoix, Mich., assignor to Union Tank Car Company, Chicago, Ill., a corporation of New Jersey

Application March 16, 1956, Serial No. 572,033

3 Claims. (Cl. 137—588)

This invention relates to a valve mechanism, and more particularly to a valve mechanism for use on a tank and the like.

It is an object of the invention to provide a valve mechanism on a tank that is readily accessible and easily operable.

It is a further object of the invention to provide a valve assembly that may be fastened as a unit to a tank.

Another object of the invention is to provide a device for sealing off a vent port and siphon conduit in a railway tank car, or the like.

Further objects and advantages of this invention will become evident as the description proceeds and from an examination of the accompanying drawing, which illustrates one embodiment of the invention, and in which similar numerals refer to similar parts throughout the several views.

In the drawings—

Figure 1 is a view in cross section taken substantially along line 1—1 of Figure 2;

Figure 2 is a plan view of a device embodying the invention with the valve in closed position;

Figure 3 is a view in cross section taken substantially along line 3—3 of Figure 1;

Figure 4 is a fragmentary view taken along line 4—4 of Figure 1, showing how the plugs are mounted on the crank arm;

Figure 5 is a fragmentary view in cross section, taken substantially along lines 5—5 of Figure 1; and

Figure 6 is a view taken substantially along line 6—6 of Figure 2.

Referring now to the drawing, reference number 10 indicates generally a valve assembly mounted on an adaptor 11. The adaptor is secured, as by welding, to a railway tank car 12 around an opening 13 therein. Through opening 13 and valve 10 the tank car can be filled or emptied of its contents. A base 20 of the valve assembly is mounted on the adaptor. A siphon conduit opening 21 and a vent port opening 22 in the base communicate with the adaptor. An O-ring 23, between the adaptor and base, seals against leakage. The siphon conduit 21 is threaded at its lower end to receive a siphon pipe (not shown) adapted to extend downwardly into the tank 12. A gear valve plate 25, which rests on the base, has gear teeth 31 at its periphery and two openings 32, 33. The openings in the valve plate may be brought into alignment with the siphon conduit and vent port openings in the base by rotation of the valve plate about its axis on the center pin 29. An O-ring 26 in a suitable groove in the top surface of the base 25 encompasses the siphon conduit 21. Another O-ring 27 in a suitable groove in the top surface of the valve gear plate encompasses the vent port 22 to prevent leakage from one to the other when the valve is being used. A similar pair of O-rings 26', 27' is provided in suitable grooves in the top surface of the valve gear plate. A third O-ring 28, retained in a suitable groove in the base encircles both openings, namely, the siphon conduit and the vent port. A similar O-

2

ring 28' is provided in the top surface of the gear valve plate.

The valve gear plate is rotated by means of a pinion 36 mounted on a square portion 37 of shaft 38. The pinion engages the teeth of the gear valve, so that as the shaft is turned, the valve plate is moved.

The shaft extends through an aperture 40 in the base into a recess 41 in the adaptor and is restricted from vertical movement by a retaining ring 42. The shaft extends upwardly through an opening 43 in housing 45.

The housing 45 has two openings 46, 47, which are located directly above vent port 22 and conduit 21 in the base. These openings are provided with threads at the upper ends for receiving threaded plugs.

15 The adaptor 11 is provided with a plurality of threaded holes 48 in the upper surface to receive stud bolts 49. These stud bolts pass through the holes 51 in the housing, and 51' in the base. The valve assembly is held by stud nuts 50 on the bolts.

20 A shoulder 52 depends from the housing to engage the base substantially around the periphery thereof, except at the location of the pinion. The shoulder is radially spaced from the gear plate to allow sufficient clearance for rotation. The center pin 29 extends between 25 the base and housing and is contained in recesses therein. The valve gear plate is adapted to rotate about the center pin between the base and housing.

The upper end of the shaft has a boss 53, to the upper surface of which a crank arm 54 is rigidly attached. A 30 pair of threaded plugs 55 is rotatably secured to the crank arm adapted to be screwed into the openings in the housing. By rotatably supporting the plugs on the crank arm, the plugs are permitted to be unscrewed to remove them from the openings. After removal from the openings, 35 the plugs may then be rotated about the crank arm to substantially upright position (shown in dotted lines in Figure 4), leaving the crank arm free to rotate. After the crank arm has been moved to open the valve to the dotted line position in Figure 2, the plugs cannot be re-

40 inserted into the openings in the housing. The crank arm must be returned to a position so that the valve plate is closed before the plugs can be replaced. As shown more particularly in Figure 4, the plugs are each provided with an enlarged knob 56. A holder 57 comprising a rod is wrapped horizontally around the plug below the enlarged 45 knob and then bent vertically around the crank arm 54. In this manner the plug is rotatably mounted on the holder and also journaled on the crank arm.

A lug 62 protrudes radially from the portion of the shaft below boss 53, as most clearly shown in Figure 5. 50 A stop 63 projects upwardly from the housing and is disposed so as to limit the rotation of the crank arm when the gear valve plate has been moved to open position by engaging the lug 62.

The valve assembly, including the housing and base 55 with the valve gear plate therebetween, is held together as a unit by pin 66 and retaining ring 67. If the bolts 49 are loosened, the valve assembly may be removed bodily from the adaptor or the tank car.

60 A downwardly extending flange 69 at the outer periphery of the housing encompasses the base and a portion of the adaptor. The flange restricts the housing from horizontal movement in the event an excessive force is exerted upon it, and affords protection against shearing of the stud bolts.

65 From the foregoing, the operation of the device should be apparent. Assuming the valve to be closed, as shown in Figure 1, the plugs are first removed from the openings in the housing and the handle rotated in a counter-clockwise direction to the position shown in dotted lines 70 in Figure 2. At this point the lug on the shaft engages the stop projecting upwardly from the housing to limit

the rotation of the handle. During the counterclockwise rotation, the pinion is also rotated in the same direction, which causes the valve gear to rotate in a clockwise direction. When the lug on the shaft engages the stop on the housing, the openings in the gear valve will be in alignment with the vent port and siphon conduit openings in the base, so as to permit the tank to be filled or emptied. After the necessary operation, the valve is closed by rotating the crank arm in a clockwise direction until the plugs are directly above the openings in the housing. The plugs are then screwed into the threaded openings. The valve is thereby closed and sealed.

In the drawing and specification, there has been set forth a preferred embodiment of the invention, and, although specific terms are employed, they are used in a generic and descriptive sense only, and not for purposes of limitation. Changes in form and in the proportion of parts, as well as the substitution of equivalents are contemplated, as circumstances may suggest or render expedient, without departing from the spirit or scope of this invention as further defined in the following claims.

I claim:

1. In a device of the character described, a valve body having a plurality of conduits, an axially mounted rotatable gear valve, a shaft, a pinion on said shaft in engagement with said gear valve, a crank arm connected to said shaft for turning said pinion, said gear valve containing a plurality of openings for alignment with said conduits in said valve body, and plug members mounted on said crank arm, said plug members being in alignment with said conduits when said gear valve is in closed position.

2. The construction comprising, an adaptor member adapted to communicate with a chamber, a base member mounted on said adaptor member, a port opening in said base member communicating with said adaptor member, a conduit opening in said base member com-

10

municating with said adaptor member, an axially mounted gear valve having openings for alignment with said port opening and said conduit opening, a pinion in engagement with said gear valve, means for rotating said pinion to open and close said valve, a housing member above said gear valve, sealing means between said base member and gear valve encircling both said port and conduit openings.

3. The valve mechanism comprising, a base member, a port opening in said base member, a conduit opening in said base member, a gear valve having openings for alignment with said port opening and said conduit opening, a pinion in engagement with said gear valve, means for rotating said pinion to open and close said valve, a housing member above said gear valve, a pair of openings in said housing member in alignment with said port opening and said conduit opening, sealing means between said base member and gear valve encircling both said port and conduit openings, and sealing means between said housing member and gear valve encircling said pair of openings in said housing member, and sealing means separately encircling said port and conduit openings.
